THE BEARDSLEY & PIPER COMPANY, OF CHICAGO, ILLINOIS, A CORPORATION OF
ILLINOIS

MACHINE FOR FILLING MOLDS FOR FOUNDRY

Application filed December 8, 1924. Serial No. 754,487.

The invention relates to machines for filling molds for founding.

One object of the invention is to provide a machine of the portable type and equipped with a reservoir for holding a load of sand from which the flasks are to be filled, which is comparatively simple in construction and easy of operation.

Another object of the invention is to provide an improved truck for a machine of this type.

Another object of the invention is to provide improved means for delivering the sand from the reservoir to the mold filling machine.

Other objects of the invention will appear from the specification.

The invention consists in the several novel features hereinafter set forth and more particularly defined by claims at the conclusion hereof.

In the drawings: Fig. 1 is a side elevation of a machine embodying the invention. Fig. 2 is a plan, the molding machine being omitted. Fig. 2^a is a detail section of a portion of the endless conveyor which forms the bottom of the reservoir. Fig. 3 is a longitudinal section of the parts shown in Fig. 2. Fig. 4 is an enlarged section taken on line 4—4 of Fig. 3. Fig. 5 is an end view of the parts shown in Fig. 4. Fig. 6 is an enlarged section taken on line 6—6 of Fig. 1. Fig. 7 is a section taken on line 7—7 of Fig. 6. Fig. 8 is an enlarged section taken on line 8—8 of Fig. 1. Fig. 9 is a section taken on line 9—9 of Fig. 8.

The invention is exemplified in a truck which is adapted to run upon a narrow track formed by rails 15 laid on the foundry floor. This truck is provided with a pair of front traction wheels 16 and a pair of rear wheels 17 which are adapted to run on the rails. The framework of this truck comprises a cast housing 18, through which the axle 19 for the traction-wheels 16 extends; a pair of sills 20 formed of channel beams secured to the housing at 21 and extending rearwardly therefrom; an end frame or bracket 22 fixed to the sills 20 and carrying stub shafts 23 for the carrying wheels 17; and a tubular

reach 24, which has its front end fixed in a socket 25 on a plate 26 which is bolted at 27 to the rear of housing 18 and its rear end fixed in a depending lug 28 on bracket 22 by a clamping member 29. The housing 18 forms an enclosure for the propelling mechanism for the truck and the sand feeding mechanism.

A reservoir 30, which is preferably elongated longitudinally and is downwardly convergent, is adapted to retain a load of sand sufficient to fill a large number of flasks. The sides of reservoir 30 are fixed to the sills 20 of the truck by means of angle bars 31 which are riveted to the reservoir and bolted to the top flanges of the sills. The top of this reservoir is open, so that it can be filled from an over-head sand delivery system or in any other suitable way. The bottom of this reservoir is formed of an endless conveyor 33 which is adapted to feed the sand forwardly through a discharge opening 34 adjacent the bottom and in the front wall of the reservoir. This conveyor consists of an endless series of slats 35 which are adapted to overlap one another to form a closure; a pair of endless link belts 36, to which lugs 37, fixed to the slats 35, are pivoted; sprocket-wheels 38 for said belts, fixed to a shaft 39, which is journalled in bearings 40 fixed to the inner sides of sills 20, and sprocket-wheels 41 on a shaft 42, which is journalled in plates 43. Plates 43 are longitudinally adjustable by means of screws 44 to keep the belts and conveyor taut.

The discharge opening 34 is normally closed by a curved gate 45 which is vertically movable to serve as a valve, whereby the height of the discharge opening may be varied to regulate the quantity of sand discharged from the reservoir. Said gate is supported by a pair of arms 46 which are pivoted to the reservoir sides at 47 so the gate can swing upwardly or downwardly. These arms are preferably hung so that ordinary pieces of scrap, which are larger than the opening, will force their way through the opening by lifting the gate so that they will not obstruct the discharge opening and thus interfere with the regulated delivery of

the sand. Mechanism is provided to raise and lower gate 45 and consists of a crank 48 journalled in a bracket 49 and carrying a worm 50 to operate a gear 51 fixed to rotate with a drum 52 and a flexible element, such as a cable 53, wound around the drum and attached at its lower end to the gate. Drum 52 is carried by the shaft 54 which is supported in bracket 55 and 56 attached to the front of the reservoir 30. Cable 53, being flexible, permits the gate 45 to be forcibly lifted by scrap on the conveyor 33 and also permits the gate to fall by gravity to its desired position after the scrap has passed through the discharge opening. The conveyor 33 is operated to feed the sand step-by-step through the discharge opening by means of a ratchet wheel 57 fixed to the projecting end of the sprocket shaft 39 and a pawl 58 on a rocker arm 59, which is pivoted on shaft 39 and is oscillated by a link 60 which is pivoted to said arm and to a wrist-pin 61^a on the outer end of a shaft 61 which is driven by gearing hereinafter described. This construction exemplifies a reservoir adapted to contain a load of sand which is provided with an endless conveyor bottom for discharging the sand in regulated quantity for delivery to the molding machine. The conveyor belt 33 discharges the sand into a screening or riddling device 62 which is disposed under and adjacent the front end of said belt. This device consists of a box 63, containing a screen 64; an inclined bottom 65 and an opening at one end adapted to discharge the screened sand into a pocket 66 formed in the housing 18. This device is of the vibratory type, being sustained adjacent its front end by a pair of vertically extending resilient strips 67, which have their upper ends attached to the box 63 and their lower ends to the bracket 26, and a pair of resilient strips 68 at the rear of box 63. Strips 68 have their upper ends attached to an angle iron 69 which is riveted to the box 63 and their lower ends secured at 70 to a bracket 71 which is recessed to fit around a portion of the tubular reach 24 and is clamped thereto by a U-bolt 72. The screening device is vibrated rapidly by wrist-pins 73 on the ends of a shaft 74 and resilient rods 73^a. An electric motor 90 is mounted in a pocket 91 in housing 18 and it is suitably coupled to drive a coaxial shaft 92, which is journalled in a bearing 93 in the housing. A pinion 94 on one end of shaft 92 meshes with a gear 95 which is keyed to the shaft 74. This motor and gearing drive the shaft 74 to operate the wrist pins 73 which vibrate the riddle or screening device. A shield 96 covers the outer end of electric motor 90. Pinion 94 and gear 95 are located in a chamber 97 on the outside of one of the side walls of the housing 23 and the outer side of this chamber is formed by a removable plate 98.

This chamber is adapted to contain a lubricant to keep this gearing properly lubricated. The housing 18 is formed, as at 99, to enclose the inner side of the motor 90, so that it will not be exposed to sand in the pocket 66. This construction exemplifies a screening device which is located to receive sand from the bottom of the reservoir and for delivering the sifted sand into a pocket from which it is conveyed for use in the molding machine.

An elevator is mounted on the truck for lifting the sand and delivering it into the conveying mechanism which is movable with and feeds the sand to the projector which slings it into the flasks. This elevator comprises a sprocket wheel 75, which is formed in sections and secured to the shaft 61; a chain 76 equipped with sand buckets 77; an overhead sprocket 78 on a shaft 79, which is mounted in levers 80 which are fulcrumed at 81 on the upper end of a column 82, which is bolted, as at 83, to the top of housing 18. This column is hollow and the descending reach of the chain and buckets pass therethrough. Sprocket 75 is disposed in the pocket 66, so that the buckets, as they pass around said sprocket, will dip into the sand from the screening device 63 and elevate it. At each side of the pocket 66, diagonal blades 84 are fixed to shaft 61 to agitate the sand and prevent it from becoming packed in the pocket, so that it will flow freely into the buckets 77. As the buckets 77 pass around sprocket 78, they discharge the sand forwardly over the top of the column 82 and into the hopper 85. The elevator chain 76 is kept taut by springs 86 which are connected to levers 80 and to cables 87. One end of each cable 87 is wound around the shaft of a ratchet wheel 88 which is mounted on one side of the column 82 and is held by a pawl 89, so that the shaft may be turned to wind up the cable 87 to vary the tension of the spring 86. This construction exemplifies one in which the sand elevator receives sand from a pocket in the truck and to which it is delivered from the reservoir carriage by the truck.

Shaft 61, which operates the wrist pin 61^a to operate the conveyor bottom 33 to feed sand to the screening device and carries the driving sprockets 75 for the elevator chain 76, is driven from shaft 74, which is driven from motor 90 as hereinbefore described, by a pinion 100 which is keyed to said shaft and a gear-wheel 101 which is fixed to one end of shaft 61. Pinion 100 and gear 101 are disposed in a chamber 102 formed on one side of the housing 18 having its outer side closed by a removable plate 103. This chamber is adapted to retain oil to keep the gearing therein efficiently lubricated. The motor 90 and gearing driven thereby exemplify mechanism by which the elevator, endless bottom

for the reservoir and the screening device may be driven from a motor mounted on the truck. Also one in which these gearings are protected from sand in the pocket 66 and kept well lubricated.

5 A molding machine for projecting wads of sand at high speed into flasks is mounted on the truck and comprises a column 105; a jib 106 mounted to swing horizontally around the column; an arm 107 pivoted on the distal end of jib 106 to swing horizontally; a projector-head 108 at the outer end of said arm and driven by an electric motor 109 on the inner end of the arm, a conveyor-belt 110 mounted to swing with arm 107 and a conveyor-belt 111, which is adapted to convey sand from the hopper 85 into which it is delivered by the elevator to the conveyor 110 on the arm which feeds the sand into the projector-head. This projector may be of the construction set forth in an application filed by us December 1, 1924, and serially numbered 753,095 to which reference may be had for further details thereof. It will be understood, however, that other forms of sand projectors, such as those set forth in our Patents Nos. 1,309,833, 1,335,642, 1,408,493 and our application No. 695,705 may be used.

10 The mechanism for driving the traction wheels to propel the truck comprises a reversible electric motor 114 which is mounted in a chamber 115 formed in housing 18; a shaft 116 mounted in a bearing 117 in the housing and coaxial with the motor 114; a pinion 118 fixed to said shaft; a gear 119, meshing with pinion 118 and mounted on a shaft 120; a pinion 121 rigid with gear 119; a gear-wheel 122 fixed to a shaft 123 which is mounted in a bearing 124 carried by a horizontal wall 125 of the housing 18; a wrist-pin 126 on one end of shaft 123 carrying a pawl 127; and a ratchet 128 loosely mounted on the traction-wheel axle 19. A clutch-collar 129 is slidable on and splined to the traction-wheel axle 19 and provided with clutch-teeth adapted to establish a driving connection between ratchet-wheel 128 and the axle 19. This pawl and ratchet are used to propel the truck slowly from flask to flask while the projector is being operated to fill them.

15 For propelling the truck at high speed, as desired in moving the machine to and from its loading point or other places and the place where the empty flasks are arranged, a pinion 130, fixed to rotate with gear 122 and shaft 123 drives a gear 131, which is loosely mounted on the traction-wheel axle and is provided with clutch teeth 132 adapted for engagement with corresponding teeth on the clutch collar 129, so that a driving relation may be established between the high speed gear 131 and axle 19. Motor 114 is of the reversible type, so that the machine may be propelled at high speed in either direction 20 through the gear 131. A controller 134 at the

front of housing 18 is fixed to a shaft 135, which is pivoted in the housing and carries, at its inner end, a fork 136 which is adapted to shift the clutch-collar 129 into engagement with either the ratchet 128 for slow forward propulsion or with the gear 131 for high speed propulsion, as well as to shift it in a neutral position when the truck is to remain stationary. The outer end of shaft 117 is supported by a bearing bracket 117^a. Pinion 118 and gear 119 are mounted in a pocket on the outside of a housing 18 which is enclosed by a removable cap 138. The remainder of the gearing for driving the traction wheels is arranged in a chamber 139 which is adapted to contain oil to keep all of the gearing well lubricated. The lower part of this chamber is formed by a shell 140 which is removably secured to the housing 18. A drain plug 141 is provided in the bottom of said shell.

25 The machine may be propelled by motor 114 and the high speed gearing 130, 131 to the point where the reservoir 30 will receive a load of sand. When the reservoir has been filled, the machine can be propelled through the same gearing and the reversal of motor 114 to the stretch where the empty flasks have been placed in readiness for filling at either or both sides of the runway for the machine, where the truck will be stopped. Next, the operator will start the motor 90 and shift the controller lever 134 to cause the truck to be propelled forwardly by means of pawl 127, ratchet-wheel 128 and clutch-collar 129. Motor 90 will operate the lower elevator shaft 61 through pinion 94, gear 95, shaft 74, pinion 100, and gear 101. This will operate the wrist-pin 61^a to operate the conveyor bottom 33 of the reservoir 30 to feed sand into the screening device 63. Simultaneously, the wrist-pins 73 will operate resilient rods or bars 73^a which have their rear ends connected to cross-bars 69 to vibrate the screening device and sift the sand delivered into it by the conveyor 33. The elevator 76, 77, will be simultaneously operated by sprockets 75 on shaft 61. The elevator will discharge sand into the hopper 85. The projector-head 108, to which sand from the hopper 85 will be continuously fed, will be moved horizontally over the flasks by an operator to sling wads of sand at high speed into all portions of the flasks. While a flask at either side of the runway is being filled, the pawl 127, ratchet 128 will advance the truck sufficiently to bring the next flask or flasks within reach of the projector-head. This may be contained until all of the sand in the reservoir 30 has been used. Thereupon, motor 90 will be stopped to stop the conveyor belt 33, the screening device and the elevator, and controller lever 134 will be shifted to put gear 131 into driving relation with the axle 19, so that the en-

tire machine may be quickly propelled to the loading point and there re-loaded.

A characteristic of the machine is that it is comparatively narrow so it may be operated over a narrow space or runway in the foundry, which is important where the economizing of space is necessary. This results from making the reservoir comparatively narrow and longitudinally elongated and arranging the reservoir, elevator and molding machine longitudinally of one another. The housing, forming part of the truck, is utilized to enclose all of the driving mechanisms, so they can be kept well lubricated and protected from sand. The use of beams and a tubular reach in the truck is advantageous in constructing the truck so that it will properly and efficiently support the several parts. The conveyor belt, forming the bottom of the reservoir and driven at slow speed, causes uniform delivery of sand from the reservoir to the screening device so that the supply of sand to the molding machine will be in predetermined rate or volume. The machine can be advantageously used in jobbing foundries where molds of different character are to be filled. The projector-head can be shifted to either side of the runway, so that flasks at either side or both sides thereof may be filled while the machine is making a run in one direction.

The invention is not to be understood as restricted to the details set forth, since these may be modified within the scope of the appended claims, without departing from the spirit and scope of the invention.

Having thus described the invention, what we claim as new and desire to secure by Letters Patent, is:

1. In combination, a relatively narrow portable truck, mechanism on the truck for propelling it, a longitudinally elongated reservoir mounted on the truck and adapted to contain a supply of sand, means for discharging sand in regulated quantity from the reservoir, a sand projector mounted on the truck, longitudinally of the reservoir, and means for delivering sand from the discharge means to the projector comprising an elevator mounted on the truck and disposed longitudinally between the reservoir and the projector.

2. In combination, a relatively narrow portable truck, mechanism on the truck for propelling it, a longitudinally elongated reservoir mounted on the truck and adapted to contain a supply of sand, a longitudinally travelling conveyor at the bottom of the reservoir for discharging sand in regulated quantity from one end of the reservoir, a sand projector mounted on the truck and longitudinally of the reservoir, and means for delivering discharged sand from the conveyor to the projector.

3. In combination, a relatively narrow

portable truck, mechanism on the truck for propelling it, a longitudinally elongated reservoir mounted on the truck and adapted to contain a supply of sand, a longitudinally travelling belt at the bottom of the reservoir for discharging sand in regulated quantity from one end of the reservoir, a sand projector mounted on the truck, longitudinally of the reservoir, and means for delivering discharged sand from the belt to the projector comprising an elevator mounted on the truck and disposed longitudinally between the reservoir and the projector.

4. In combination, a relatively narrow portable truck, mechanism on the truck for propelling it, a longitudinally elongated reservoir mounted on the truck and adapted to contain a supply of sand, means for discharging sand in regulated quantity from the reservoir, a sand projector mounted on the truck, longitudinally of the reservoir, means for delivering discharged sand from said means to the projector, comprising an elevator on the truck disposed longitudinally between the reservoir and the projector, and a screening device between the discharge means and the elevator.

5. In combination, a relatively narrow wheeled truck, mechanism on the truck for propelling it slowly in one direction and at high speed in said direction and in the opposite direction, a longitudinally elongated reservoir mounted on the truck and adapted to contain a load of sand, means for discharging sand in regulated quantity from one end of the reservoir, an elevator disposed longitudinally of one end of the reservoir, means to deliver discharged sand to the elevator comprising a screen mounted on the truck, and a molding machine mounted on the truck, disposed longitudinally of the elevator, and to which sand is fed from the elevator.

6. In combination, a relatively narrow portable truck, means on the truck for propelling it, a reservoir on the truck adapted to contain a load of sand, an endless conveyor at the bottom of said reservoir adapted to discharge sand in regulated quantity from the reservoir, a sand projector mounted on the truck, means for delivering sand to the projector, comprising a screening device receiving the sand from the conveyor and an elevator to which the screened sand is delivered, and means on the truck for driving the conveyor.

7. In combination, a relatively narrow portable truck, means on the truck for propelling it, a reservoir on the truck adapted to contain a load of sand, an endless conveyor belt forming the bottom of said reservoir, a gate to control the discharge of sand by the conveyor, a sand projector mounted on the truck, means for delivering sand from the

discharge means for the projector, and means on the truck for driving the belt.

8. In combination, a relatively narrow portable truck, means on the truck for propelling it, a reservoir on the truck adapted to contain a load of sand, an endless conveyor belt at the bottom of said reservoir adapted to discharge sand in regulated quantity from the reservoir, a sand projector mounted on the truck, means for delivering sand from the discharge means to the projector, and means on the truck for driving the belt, comprising a pawl and ratchet and a motor.

9. The combination of a truck, a reservoir adapted to contain a supply of sand, mounted on the truck, a screening device mounted on the truck below the reservoir, means for feeding sand in regulated quantity from the bottom of the reservoir to said screening device, an elevator mounted on the truck to receive sand from the screening device, a sand projector mounted on the truck, to which sand is fed from the elevator.

10. The combination of a truck provided at one end thereof with a pocket, a reservoir adapted to contain a supply of sand, mounted on the truck, a screening device mounted on the truck below the reservoir and adapted to discharge sand into said pocket, means for feeding sand in regulated quantity from the bottom of the reservoir to said device, an elevator mounted on the truck to lift sand from the pocket, a sand projector mounted on the truck and to which the elevated sand is fed, and mechanism on the truck for operating said device and driving the elevator.

11. The combination of a portable truck, mechanism mounted on the truck for propelling it at low speed in one direction and at high speed in said direction and in the opposite direction, a reservoir for sand mounted on the truck, means for discharging sand in regulated quantity from the bottom of the reservoir, the truck being provided with an enclosed pocket into which the sand is delivered from the reservoir, a sand elevator mounted on the truck, having its lower end operating in said pocket, a sand projector mounted on the truck, to which sand is fed from the elevator, and mechanism on the truck for driving the elevator.

12. The combination of a portable truck, mechanism mounted on the truck for propelling it, a reservoir for sand mounted on the truck, an endless conveyor forming the bottom of the reservoir for discharging sand in regulated quantity from the reservoir, the truck being provided with an enclosed pocket into which the sand is delivered from the conveyor, a sand elevator mounted on the truck and having its lower end operating in said pocket, and a sand projector mounted on the truck, to which sand from the elevator is fed.

13. The combination of a wheeled truck comprising a housing, a reservoir for containing a load of sand, mounted on the truck, a sand projector mounted on the truck, mechanism for delivering sand from the reservoir to the projector in regulated quantity comprising a screening device and an elevator, gearing for operating the elevator, and the screening, enclosed in said housing, and a motor mounted on the truck for driving said gearing.

14. The combination of a wheeled truck comprising a housing, a reservoir for containing a load of sand, mounted on the truck, a sand projector mounted on the truck, mechanism for delivering sand from the reservoir to the projector in regulated quantity comprising a device for discharging sand from the bottom of the reservoir, a screening device, and an elevator, gearing for operating the elevator, the screening device and discharge device, enclosed in said housing, and a motor mounted on the truck for driving said gearing.

15. The combination of a wheeled truck comprising a housing provided with a pocket, a reservoir for containing a load of sand mounted on the truck, a sand projector mounted on the truck, mechanism for delivering sand from the reservoir to the projector in regulated quantity comprising means to discharge sand into the pocket from the bottom of the reservoir, a screening device, and an elevator, gearing for operating the elevator, screening device and discharge device, enclosed in said housing, and a motor mounted on the truck for driving said gearing.

16. The combination of a wheeled truck comprising a housing, mechanism for propelling the truck comprising a motor and gearing, enclosed by said housing, a reservoir mounted on the truck adapted to contain a load of sand, a sand projector mounted on the truck, means for delivering sand in regulated quantity from the reservoir to the projector comprising a discharge device, a screening device and an elevator, and gearing for operating said devices and the elevator, also enclosed by said housing.

17. The combination with a portable truck comprising a housing, traction and carrying wheels, and a tubular reach secured to the housing, of a reservoir for containing a load of sand mounted on said truck, mechanism for driving the traction wheels, a sand projector mounted on the housing, and mechanism mounted on the truck for delivering sand in regulated quantity from the reservoir to the projector comprising a screening device supported on the tubular reach.

18. The combination with a portable truck comprising a housing, traction and carrying wheels, and beams and a tubular reach secured to the housing, of a reservoir for con-

taining a load of sand mounted on said beams, mechanism for driving the traction wheels enclosed in said housing, a sand projector mounted on the housing, and mechanism for delivering sand in regulated quantity from the reservoir to the projector, comprising a movable bottom for discharging sand from the reservoir, a screening device for the discharged sand, and an elevator to which the sand is delivered by said screening device, and driving mechanism for said bottom, device and elevator mounted in said housing.

19. The combination of a portable truck, means on the truck for driving it, a reservoir adapted to contain a load of sand mounted on the truck, a screening device below the reservoir, means to discharge sand from the reservoir to said device, an elevator to which sand from the screening device is delivered, a motor on the truck, gearing for driving the discharge means, screening device and the elevator from the motor and a sand projector to which sand is delivered from the elevator mounted on the truck.

Signed at Chicago, Illinois, this 22nd day of October, 1924.
